(57) **CLAIM**

We claim the ornamental design for a baby bottle, as shown and described.

DESCRIPTION

FIG. 1 is a perspective view of a baby bottle.

FIG. 2 is a top view of the baby bottle shown in FIG. 1.

FIG. 3 is a bottom view of the baby bottle shown in FIG. 1.

FIG. 4 is a left side view of the baby bottle shown in FIG. 1.

FIG. 5 is a right side view of the baby bottle shown in FIG. 1.

FIG. 6 is a front view of the baby bottle shown in FIG. 1.

FIG. 7 is a rear view of the baby bottle shown in FIG. 1.

FIG. 8 is a perspective view of another alternative construction of a baby bottle.

FIG. 9 is a top view of the baby bottle shown in FIG. 8.

FIG. 10 is a bottom view of the baby bottle shown in FIG. 8.

FIG. 11 is a left side view of the baby bottle shown in FIG. 8.

FIG. 12 is a right side view of the baby bottle shown in FIG. 8.

FIG. 13 is a front view of the baby bottle shown in FIG. 8; and,

FIG. 14 is a rear view of the baby bottle shown in FIG. 8.

Broken lines illustrating the environment form no part of the claimed design.

1 Claim, 8 Drawing Sheets
